UNITED STATES PATENT OFFICE

146,267

DESIGN FOR AN ASH TRAY

Hayes A. Quigley, Akron, Ohio

Application September 28, 1945, Serial No. 122,376

Term of patent 3½ years

(Cl. D85—2)

To all whom it may concern:

Be it known that I, Hayes A. Quigley, a citizen of the United States, residing at Akron, in the county of Summit and State of Ohio, have invented a new, original, and ornamental Design for Ash Tray, of which the following is a specification, reference being had to the accompanying drawing, forming part thereof.

Of the accompanying drawing:

Fig. 1 is a plan view of an ash tray, showing my new design;

Fig. 2 is a side elevation thereof; and

Fig. 3 is a perspective view of the ash tray with the parts thereof in separated relation.

I claim:

The ornamental design for an ash tray, substantially as shown.
